ADJUSTABLE ANTENNA

Samuel J. Spector, New York, N. Y., assignor to
Insuline Corporation of America, Long Island
City, N. Y., a corporation of New York

Application May 3, 1949, Serial No. 2,399

Term of patent 3½ years

(Cl. D26—14)

To all whom it may concern:

Be it known that I, Samuel J. Spector, a citizen of the United States and a resident of New York, New York, have invented a new, original, and ornamental Design for an Adjustable Antenna, of which the following is a specification, reference being had to the accompanying drawing, forming part hereof, in which:

Fig. 1 is a top plan view of an adjustable antenna showing my new design with the antenna arms in an extended position;

Fig. 2 is a front elevational view thereof with the antenna arms in an upright position; and

Fig. 3 is an end elevational view of Fig. 2,

I claim:

The ornamental design for an adjustable antenna, as shown.

SAMUEL J. SPECTOR.
